UNITED STATES PATENT OFFICE.

HECTOR RABEZZANA, OF FLINT, MICHIGAN, ASSIGNOR TO A C SPARK PLUG COMPANY,
OF FLINT, MICHIGAN.

SPARK PLUG.

Application filed March 1, 1926. Serial No. 91,487.

- The invention relates to a spark plug, and more particularly to improvements in the method of securing the side electrode wire to the shell thereof.
- 5 One of the objects of my invention is to provide a practical, simple and inexpensive means of expanding an electrode wire inside an aperture in the wall of the shell.
- Other objects will appear hereinafter.
- 10 The invention consists in the novel arrangement and construction of parts more particularly described in the following specification and pointed out in the annexed claims.
- 15 In the accompanying drawing:
- Figure 1 is a diagrammatical view showing, partly in section, an elevation of a spark plug, and illustrating the method of fastening a side electrode wire inside the shell thereof.
- 20 Figure 2 is a view similar to Figure 1, showing an abbreviated form of side electrode, and the use of a pair of pivoted gripping jaws.
- 25 Figure 3 is a similar view showing a modified form of the side electrode, and a pair of jaws formed with a relatively deep gripping surface.
- 30 Figure 4 is a part sectional, elevational view of the plug shown in Figure 2 in finished form.
- Like numerals of reference indicate similar parts in the different figures. In Figure 1, the spark plug 5 has its wall formed with diametrically disposed inwardly tapering apertures 6. A side electrode 7, consisting, in this instance, of a continuous wire extending across the plug, is expanded, or wedged, inside the tapered apertures 6.
- 35 To accomplish this purpose, I have provided an implement connected with an electrical current and comprising a gripping body portion 9, carrying at one end a flat metallic shoe or cap 10, which forms one side of a transformer line, as indicated in the drawing. A control switch 11 is provided. The implement 8 is brought against one end of the electrode, the other end being received by a suitable stationary object 12 as shown in Figure 1. The switch 11 is then closed and a firm momentary pressure is applied. The side electrode wire 7 is made to assume an intermediate metallic union with the wall of the spark plug. The 40 electrical current and pressure causes the wire to expand or swell until it fits tightly, at which point the operation becomes completed. It will be obvious that if the operation would continue over a longer period, a welding between the parts would be effected, which I aim to obviate. The electrode wire in spark plugs of this type is usually of nickel or some alloy thereof which is of lower melting point than the material of the spark plug wall or shell, which is ordinarily steel.
- 45 It will be understood that the above described means of fastening the side electrode wire 7 in place, falls short of a weld, and is, in substance, a mere forced fit.
- 50 In lieu of the implement 9, a pair of recessed jaws 13 (see Figure 2) may be used. In Figure 3, I have shown the said recessed jaws formed with a more extensive recess by which the electrode wire may be engaged.
- 55 The jaws 13 preferably constitute one extremity of a pair of insulated pincers (not shown) connected to an electrical circuit in a similar manner as disclosed in Figure 1.
- 60 Obviously, the said jaws may be either long or short, but it will be evident that by having longer jaws (as shown in Figure 3), the electrode wire 7 is more completely surrounded, and, of course, the heating of the electrode is effected in a comparatively shorter time.
- 65 In Figure 2, a member 14 is inserted within the plug to properly position the said electrode wire during the expanding operation. In this instance, since the wire does not extend wholly across the plug an important economy in material and operation, obviously, is effected. In Figure 3, a vertically drilled aperture, having a diameter somewhat greater than the electrode wire 7, is utilized rather than the tapered aperture of Figures 1 and 2.
- 70 It will be understood that any surplus material remaining after the above described operation, may readily be removed in the threading operation of the plug.
- 75 From the foregoing it will be seen that I have provided a construction, disposition and combination of parts which fully attains the object of my invention.
- 80 Modifications of the above may be made within the spirit and scope of my invention.
- 85 What I claim is:
1. A spark plug including an electrode wire, a bottom wall provided with orifices 110

of diameters somewhat larger than the diameter of the said wire, to receive the ends of the said electrode wire expanded thereinto by a combined heating and pressing 5 operation, the said wire being connected to the wall of the spark plug in an intermediate union less than a weld.

2. A spark plug including a wall formed with a tapered orifice, an electrode extended 10 therethrough, and having an expanded portion conforming to the shape of the said orifice.

3. A spark plug including a wall formed with two oppositely disposed tapered orifices, an electrode running across the said 15 plug and having its ends expanded in a forced fit to conform to the interior of the said orifices.

4. The combination in a spark plug of 20 a metallic shell and a metallic electrode wire, the shell having a recess of larger

diameter than the said wire, one end of said electrode being positioned within said recess and expanded therein to fit the recess, thereby supporting the electrode and 25 providing electric conducting contact between the electrode and the shell.

5. The method of securing a spark plug electrode to a spark plug shell comprising providing in the shell a recess of greater diameter than the electrode, positioning a portion of the electrode in said recess, engaging the portion of the electrode which projects from the recess with a tool adapted to supply heating current to said electrode, and 30 applying heating current and pressure to said electrode by means of said tool, thereby expanding the portion within the recess.

In testimony whereof I affix my signature.

HECTOR RABEZZANA.
